UNITED STATES PATENT OFFICE.

HORACE J. BOON, OF HARTFORD, CONNECTICUT, ASSIGNOR TO VEEDER
MANUFACTURING COMPANY, A CORPORATION OF CONNECTICUT.

SUPPORTING-BRACKET FOR ODOMETERS, &c.

No. 853,839.

Specification of Letters Patent.

Patented May 14, 1907.

Application filed July 12, 1906. Serial No. 325,785.

To all whom it may concern:

Be it known that I, HORACE J. BOON, a citizen of the United States, residing at Hartford, in the State of Connecticut, have invented certain new and useful Improvements in Supporting-Brackets for Odometers, &c., of which the following is a specification, reference being had to the accompanying drawings, forming a part hereof.

Odometers and other registering or indicating instruments, such as are commonly employed on automobiles to register distance traveled or to show the speed of travel, are sometimes mounted upon the axle or other part of an automobile in close proximity to the wheel, and sometimes they are mounted upon the body of the automobile, remote from the wheel, motion being transmitted from suitable actuating devices which are mounted in proximity to the wheel. Such instruments or the actuating devices therefor must be mounted or supported with a considerable range of adjustability in order that they may be applied readily to automobiles of different styles or makes.

It is the object of this invention to provide a supporting bracket for such an instrument or for the actuating device thereof which shall be capable of easy application to any ordinary vehicle, shall permit ready and exact adjustment of the instrument or actuating device, shall retain the instrument or actuating device firmly in position when adjusted, and shall be simple in construction, comprising but few parts.

The invention will be more fully explained hereinafter with reference to the accompanying drawings in which it is illustrated and in which—

Figure 1 is a detail view, partly in section, illustrating the application of one form of the improved bracket. Fig. 2 is a detail top view of the clamp shown in Fig. 1. Fig. 3 is a view similar to Fig. 1 but showing a different form of clamp. Fig. 4 shows end and side views of one of the balls. Figs. 5 and 6 show side and end views of different forms of connecting bars or stems.

In both Figs. 1 and 3 the improved supporting bracket is represented as applied, as usual, to the front "knuckle-joint" *a* of the steering mechanism of an automobile. The clamp by which it is thus secured is prefer-

ably of the character shown in Fig. 1, since such a clamp can be applied readily to arms or bars of different widths. As shown, the clamp comprises two jaws *b* and *c*, preferably supplied respectively with adjustable, hardened steel points, *d*, the jaws being suitably shaped to engage an arm or bar, such as *a*. The jaws are united and firmly engaged with the arm or bar *a* by a bolt *e* and nut *e'*, shims *e*² being provided between the bases of the two jaws if desired. The head *e*³ of the bolt *e* may be provided with a pin *e*⁴ to engage a recess in the jaw *b*, or vice versa, to hold the bolt from turning in its seat. The head is also recessed, as at *e*⁵, to form a socket for one of the balls hereinafter mentioned and is also screw threaded to receive an annular cap *f* by which the ball is secured in such socket.

The plate or base *g* to which the indicating or measuring instrument or the actuating device therefor is secured by any suitable means, has a similar head *g'*, recessed to form a socket *g*² and screw threaded to receive an annular cap *h*.

Between the two heads *e*³ and *g'* is interposed a stem or connecting bar *i* which may have any desired shape according to the conditions of use of the device. As shown in Figs. 1 and 3 the stem *i* is relatively short and straight. In Fig. 5 the stem or connecting bar is shown as having a double bend, while in Fig. 6 the stem or connecting bar *i*² is shown as having a single bend. Upon each end of the stem or connecting bar is applied a ball *k* adapted to fit in the corresponding socket *e*⁶ or *g*² and to be held fast therein by the annular screw threaded cap *f* or *h*. In order that one stem or connecting bar may be substituted readily for another the balls *k* are split upon one or more lines, as at *k'*, so that they can be detached readily from one stem or bar and applied to another and yet shall grip the stem or bar firmly when the cap *f* or *h* is screwed home to lock the bar in adjusted position. The stem may be knurled or otherwise formed with a suitable surface to be gripped within the bore *k*² of the ball.

It will be observed that when the clamp *b*, *c* has been screwed properly to the arm or bar *a*, the plate or base *g*, for the measuring instrument or actuating device can be placed exactly as required by the shifting of the balls *k* in their respective sockets and by the

use of a suitable stem or connecting bar, and can there be held firmly by screwing up the caps *f* and *h*.

In the construction shown in Fig. 3 the jaws *b'* and *c'* of the clamp are extended so as to straddle the arm or bar *a* and are united on opposite sides of the arm or bar *a* by bolts *e'*, the jaw *b'* being provided with a socket head *e''* to co-operate with the corresponding ball *k*. This form of clamp provides for a very firm engagement with the arm or bar, but it is less convenient in use than the single clamp shown in Fig. 1, as various lengths of jaws must be provided to accommodate different widths of arms.

I claim as my invention:

1. A supporting bracket for odometers etc. comprising a bolt having a socketed head and an annular cap, a nut for said bolt, jaws carried by said bolt and adapted to be clamped upon the supporting arm or bar, the supporting plate or base having a socket and an annular cap, and a connecting stem or bar having balls at its ends to engage said sockets and be held therein by said caps.
2. A supporting bracket for odometers etc. comprising a bolt having a socketed head and an annular cap, a nut for said bolt, jaws carried by said bolt and adapted to be clamped upon the supporting arm or bar, the supporting plate or base having a socket and an annular cap, and a connecting stem or bar having split balls at its ends to engage said sockets and be held therein by said caps.
3. A supporting bracket for odometers, etc., comprising a pair of jaws adapted to engage a portion of a vehicle, a bolt for securing said jaws in place, a socket in the head of said bolt, a supporting arm having a ball adapted to rest in said socket, and a clamping member for securing said ball in place in said socket.
4. A supporting bracket for odometers, etc., comprising a pair of jaws adapted to engage a portion of a vehicle, a bolt for securing said jaws in place, a socket in the head of

said bolt, a supporting arm having a ball adapted to rest in said socket, and an annular cap in threaded engagement with the head of said bolt and adapted to engage said ball to clamp it in place in said socket.

5. A supporting bracket for odometers, etc., comprising a pair of jaws adapted to engage a portion of a vehicle, a bolt extending through openings in said jaws and by which they are secured in place, a socket in the head of said bolt, a supporting arm, a split ball upon the end of said arm and separable therefrom and adapted to rest in said socket, and an annular cap in threaded engagement with the head of said bolt and adapted to engage said ball to clamp it in place in said socket and to clamp said ball and arm together.

6. A supporting bracket for odometers, etc., comprising a clamp adapted to engage a portion of a vehicle, a socket carried by said clamp, a supporting arm, a split ball upon the end of said arm and separable therefrom and adapted to rest in said socket, and an annular cap in engagement with said socket and adapted to engage said ball to clamp it in place and to clamp said ball and arm together.

7. A supporting bracket for odometers, etc., comprising a clamp adapted to engage a portion of a vehicle, a socket carried by said clamp, a supporting plate, a socket carried by said plate, a supporting arm extending between said clamp and plate, a split ball upon each end of said arm, and separable therefrom and adapted to rest in said sockets, and an annular cap in threaded engagement with each of said sockets and adapted to engage said balls to clamp them in place in their respective sockets and to clamp said balls to the ends of said arm.

This specification signed and witnessed this 7th day of July, A. D., 1906.

HORACE J. BOON.
